(57) **CLAIM**

The ornamental design for a tail lamp for a vehicle, as shown and described.

DESCRIPTION

FIG. 1 is a front left top perspective view of a tail lamp for a vehicle according to the present invention.

FIG. 2 is a front left perspective view of the tail lamp shown in FIG. 1.

FIG. 3 is another front left perspective view thereof.

FIG. 4 is rear right top perspective view thereof.

FIG. 5 is a front view thereof.

FIG. 6 is a rear view thereof.

FIG. 7 is an enlarged left side view thereof.

FIG. 8 is an enlarged right side view thereof.

FIG. 9 is a top view thereof.

FIG. 10 is a bottom view thereof; and,

FIG. 11 is another front view of the tail lamp shown in FIGS. 1-10, but mounted on a vehicle and with the rest of the vehicle shown in broken lines.

Any elements shown in broken lines form no part of the claimed design, but are instead included to show environmental aspects thereof.
